UNITED STATES PATENT OFFICE.

THOMAS H. WILLISON, OF ROCHESTER, NEW YORK.

CLAMP FOR SOLDERING EAVES TROUGHS.

Application filed April 18, 1922. Serial No. 555,528.

To all whom it may concern:

Be it known that I, THOMAS H. WILLISON, a citizen of the United States, residing at Rochester, in the county of Monroe and 5 State of New York, have invented certain new and useful Improvements in Clamps for Soldering Eaves Troughs, of which the following is a specification.

The object of this invention is to provide a new and improved clamping or locking device with which the ends of two eaves trough sections can be held together overlapping each other while they are being soldered together at the joint.

Another object of this invention is to make the clamping device so that it can be applied to eaves trough sections that are already supported and fastened in place under the edge of the roof of the house.

These and other objects of this invention will be fully illustrated in the drawing, described in the specification and pointed out in the claims at the end thereof.

In the accompanying drawing:
25 Figure 1 is a perspective view of the clamping or locking device as it appears when applied to the overlapping ends of two eaves trough sections for the purpose of holding these ends together while they are 30 being soldered together.

Figure 2 is a vertical longitudinal section through the overlapping ends of two eaves trough sections and the clamping device for holding these ends together.

35 In the several figures of the drawing like reference numerals indicate like parts. It is the usual practice except in long straight runs to support each section of the eaves trough or gutter in its hanger under 40 the edge of the roof before the joints between them are soldered to make the joints between the sections water tight. The eaves trough sections are supported in their hangers with the ends of the section overlapping 45 each other so that these ends can be soldered together. In soldering these lap joints it often happens that the ends of the eaves troughs are bent and therefore do not properly nest with each other due to 50 this or other causes and in such cases the walls of the eaves trough sections are out of alignment with each other. In such imperfect joints between the eaves trough sections the air gaps formed between the walls 55 of the sections to be joined must be closed before the overlapping portions of the walls

of the eaves trough sections can be soldered together. To bring the ends of two eaves trough sections together so that the joint can be soldered is frequently difficult due 60 to the fact that the eaves trough is mounted directly under the edge of the roof which leaves but little room for the workman to hold the walls of the overlapping sections together with one hand while soldering the 65 joint with his other hand. Any means with which the ends of two overlapping eaves trough sections are to be held together to bring them in line with each other must, therefore, be constructed so that it can be 70 applied and adjusted in the limited space between the edge of the roof and the eaves trough.

The clamping and locking device forming the subject matter of my invention is especially adapted for this purpose. This device comprises the semi-circular metal band 1 which conforms to the outer curvature of the eaves trough sections that are to be clamped and locked together with it. The 80 rear end of this band is perforated with a hole 2 and the front of the band is slightly offset to form a shoulder 3 thereon. This shoulder engages under the rolled edge of the eaves trough sections as illustrated in 85 Figure 1 and the free end 4 of the front of the band projects up on the outside of the rolled edge. In the end 4 of the metal band 1 is provided the hole 5 and a tapered slot 6 is cut into the side of the end 4 90 which slot leads into the side of the hole 5 for a purpose that will presently appear.

Mounted to swing between the ends of the metal band 1 is the semi-circular plate 7. This plate is fastened to the horizontal 95 shaft 8 and the ends of the shaft 8 are adapted to engage into the hole 2 in the rear and the hole 5 in the front of the metal band. For this purpose the shaft 8 projects out from either end of the semi-circular plate 7 and both the rear end 9 and the front end 10 of the shaft 8 are slightly bent as illustrated in Figure 1.

The clamping and locking device is applied as follows:

105 The ends of two eaves trough sections are first nested in the manner illustrated in the figures. Then the metal band 1 is applied to the under side of the outer eaves trough section, intermediate of the 110 overlapping ends of both of the eaves trough sections. The metal band is held in place on

The condenser *g* or the pipes *n* or the retorts *b* and *c* may be provided with an injector (indicated by *o* at one of the pipes *n* in Fig. 2, and by *o'* at one of the retorts *b* 5 in Fig. 1) for the introduction of a fine spray of water, steam, or other condensable vapors or gases, to assist in the precipitation of the material suspended in the gases and vapors developed during and by the drying and 10 burning process or carried away otherwise.

The heating of the conveyor *a* for drying the material and the heating of the burning retorts or vessels *b* and *c* for burning the material under treatment, may be effected in 15 any suitable way, using any suitable fuel and either direct or indirect heating. Superheated steam, for instance under pressure, may be applied.

In the example represented in the annexed 20 drawing, I have shown indirect heating of the material under treatment, the burning retorts or vessels being heated by means of a coal-fire on an iron grate *p*. The hot gases of this coal-fire, which have first been 25 used for heating the burning retorts *b* and *c*, may, prior to their escape into the open air through the chimney *k*, be utilized for the preliminary drying of the material which is to be subjected to burning subsequently.

30 The condensation of the condensable part of the gases and vapors developed during the drying and burning process, may also be effected by leading said gases and vapors in any suitable way through any suitable 35 liquid, say, water.

To accomplish this purpose, I may, for instance, use a condenser such as shown in Fig. 3.

The particles of the finely divided material 40 contained in the said gases and vapors are then precipitated or carried down by the particular liquid used, and may be recovered by any suitable means, e. g. by using a suitable filter, filter-press, centrifugal separator 45 or subsiding tank and the like.

In Fig. 3 of the annexed drawing, *D* represents the condenser, *A* the inlet of cold water or other liquids, *B* the inlet for the gases and vapors developed by and during 50 the drying and burning process, this inlet being connected with the pipes *n* of Figs. 1 and 2; and *C* represents the various conical baffle plates which serve for intimately mixing the said liquids with the said gases and 55 vapors.

E represents the outlet for the mixture of the said liquids with the said gases and vapors. *F* represents the outlet for the non-

condensable gases and vapors which are not removed through the outlet *E*. 60

The drying trough or receptacle *a* and the burning retorts or vessels *b* and *c* may be imbedded in a suitable setting, say as shown in Figs. 1 and 2.

I claim as my invention: 65

1. In an apparatus for drying, burning, and recovering finely divided material such as powdered decolorizing carbon, a furnace, a plurality of retorts connected in tandem fashion and located at different distances 70 from the combustion chamber of said furnace so as to be exposed to different degrees of heat, a condenser and a separate connection thereto from the upper spaces of each of the heated retorts. 75

2. In an apparatus for drying, burning, and recovering finely divided material such as powdered decolorizing carbon, a plurality of retorts connected in tandem fashion and adapted to receive successively the fine material to be treated, means for heating the successive retorts to different temperatures, a condenser and a separate connection thereto from the upper spaces of each of the heated retorts. 80

3. In an apparatus for drying, burning, and recovering finely-divided material such as powdered decolorizing carbon, a plurality of horizontal retorts connected in tandem fashion and adapted to receive successively 90 the fine material to be treated, means for heating the successive retorts to different temperatures, and a condensing device, said device being connected with the upper spaces of each of said retorts, for precipitating and collecting the particles of the material carried off by the gases and vapors produced in said retorts. 95

4. In an apparatus for drying, burning, and recovering finely-divided material, a 100 plurality of stationary horizontal retorts connected in tandem fashion and having means for mechanically transporting the material, means for heating the successive retorts to different temperatures, and a condensing device, said device being connected with the upper spaces of each of said retorts, for precipitating and collecting the particles of said material carried off by the gases and vapors produced in said retorts. 105

In testimony whereof, I affix my signature in the presence of two witnesses.

DR. ABRAHAM WIJNBERG.
